PIPETTE

Filed Dec. 2, 1936

UNITED STATES PATENT OFFICE

2,091,404

PIPETTE

Fred L. Hicks, Jackson, Tenn.

Application December 2, 1936, Serial No. 113,888

1 Claim. (Cl. 23—259)

My invention relates generally to pipettes, and particularly to a device of this type which involves a manually operated compression forming and releasing unit, and an important object of 5 my invention is to provide a simple and efficient arrangement of this character.

Another important object of my invention is to provide in a pipette, a manually operated compression forming and releasing unit which can 10 be mounted on or connected with standard pipettes.

Other important objects of my invention will be apparent from a reading of the following description taken in connection with the drawing, 15 wherein for purposes of illustration I have shown preferred embodiments of my invention.

In the drawing:—

Figure 1 is a general side elevational view of an embodiment of my invention.

Figure 2 is an enlarged longitudinal sectional view taken through Figure 1.

Figure 3 is a horizontal sectional view taken through Figure 2 approximately on the line 3—3 and looking downwardly in the direction of the 25 arrows.

Figure 4 is a view similar to Figure 1 of another embodiment of my invention.

Referring in detail to the drawing, and particularly to the embodiment of the invention shown 30 in Figures 1 and 2, the compression unit which is generally designated 5 comprises the glass or other suitable material tube 6 which has an open lower end 7 on which is threaded as indicated by the numeral 8 a metallic or other suitable material cap 9 which acts as a retainer for the lower end of the helical expanding spring 10. The cap has in its center an opening 11.

The upper part of the tube or cylinder 6 has therein a partition 12 produced by a thickening of 40 the wall of the tube, which partition defines the small longitudinal passage 13 and the relatively larger plunger barrel 14 in which the plunger or piston 15 works.

The piston is fastened to the upper end of the 45 leg 16 of the plunger 17 whose other leg works in the passage 13. The upper end of the passage 13 is extended as indicated by the numeral 18 and closed by a threaded cap 19 through which the notched portion 20 of the plunger operating rod 40 handle 17 works. The upper end of the helical spring 10 has a member 21 which seats it on the bight portion of the plunger operating rod 17 as clearly shown in Figure 2.

The upper end of the passage 14 or plunger barrel is tapered and curved as indicated by the 55

numeral 22 to enter the top of the pipette 23 which has the usual tapered lower end 24.

The embodiment of the invention shown in Figure 4 is the same as that described except that the elbow 25' while corresponding in shape to 5 the elbow 25 of the already described embodiment is cut off at the point 26, where it is provided with a ground joint 27 to receive the ground and tapered upper end 28 of a standard pipette 23', where it is desired to adapt the device of the 10 invention for operation of standard pipettes and the like. The upper end of the plunger operating rod has a button 29 facilitating its operation. The tube 6 acts as the handle for the device. If desired the connection between the pipette 23' 15 and the elbow 25' in the embodiment of the invention shown in Figure 4 may be effected by the use of the common laboratory hollow rubber stopper or any suitable connector to make the two units rigidly connected to form the complete 20 instrument.

To operate the device of the invention in measuring or transferring liquids from one container to another, the thumb button 29 is pressed downwardly so as to force the piston 15 downwardly in the piston barrel 14 while the lower end of the pipette tube 23 or 23' is in the solution, so as to engage one of the notches 20 with the cap 19. When the transfer of the instrument has been effected, the button 29 is released 25 by disengaging the notch from the cap 19, and the coil spring 10 will force the piston to its original position so as to empty the hollow glass tube or pipette 23. The "last drop" which may remain in the pipette tip 24 may be removed by 30 first compressing the button 29 slightly to allow the piston to return to a higher level than the 35 level from which the liquid was taken up.

Although I have shown and described herein preferred embodiments of my invention, it is to 40 be definitely understood that I do not desire to limit the application of the invention thereto, and any change or changes may be made in the materials and in the structure and arrangement of the parts, within the spirit of the invention 45 and the scope of the subjoined claim.

What is claimed is:—

A device of the character described comprising a pipette tube having an open lower end and an upper end of arcuate elbow form terminating 50 in a short leg of enlarged diameter as compared to the remainder of said tube and parallel with the remainder of said tube, said short leg having a longitudinal partition therein adjacent the upper end thereof extending part way into said end 55

and dividing the latter into two relatively large and small cylinders, the larger one forming a continuation of the tube and the smaller one being open at both ends, a U-shaped plunger rod having long and short portions, respectively, spanning said partition, the longer portion extending through the smaller cylinder out of the upper end thereof and the shorter portion ex-

tending into the larger cylinder, a piston on the shorter portion of said plunger within the larger cylinder, and a compression spring in said upper end of the pipette tube tensioning said plunger against movement in the direction tending to draw liquid into said pipette tube.

FRED L. HICKS.
